UNITED STATES PATENT OFFICE.

HARRY B. MAXWELL, OF ROME, NEW YORK.

CARBURETER.

No. 863,739.

Specification of Letters Patent.

Patented Aug. 20, 1907.

Application filed October 9, 1905. Serial No. 281,871.

To all whom it may concern:

Be it known that HARRY B. MAXWELL, of Rome, in the county of Oneida and State of New York, has invented certain new and useful Improvements in Carbureters; and he does hereby declare that the following is a full, clear, and exact description thereof, which will enable others skilled in the art to which it appertains to make and use the same, reference being had to the accompanying drawings, and to the letters 10 of reference marked thereon, which form part of this specification.

The object of my present invention is to provide a carbureter for explosive engines, wherein provision is made for obviating flooding when the carbureter is 15 thrown out of its normal horizontal position, as frequently occurs in automobiles and small boats.

The further object is to provide a carbureter of compact, simple and efficient construction, capable of producing the best mixture under a large variety of 20 conditions of use.

Figure 1 shows a side elevation of the carbureter, a small portion being broken off to reduce the size of the figure. Fig. 2 shows in the main a side elevation, as seen in position on a quarter turn, as shown in Fig. 25 1, a portion being shown in section to better illustrate the construction. Fig. 3 is a sectional view taken substantially on line A—B of Fig. 2. Fig. 4 is a side elevation of the throttling valve, removed from the casing. Fig. 5 is another detail view of the same 30 shown at a position at right angles to that of the view shown in Fig. 4. Fig. 6 is a plan view of the same throttling valve.

Referring to the reference letters and figures in a more particular description of the device, 1 indicates 35 the cylinder body of the carbureter, which in the main constitutes a fluid receptacle and has axially therethrough an opening affording a passage for the air for the mixture. The upper and lower ends of the receptacle casing 1 are closed by heads 2 and 3, 40 each provided with a passage coinciding with the axial passage through the casing 1. To the head 2 is attached, preferably by means of flange couplings 4, the pipe 5 extending to the explosive engine. This pipe connects with the passage extending axially 45 through the casing.

Extending radially into the casing 1, which is preferably round, is the valve casing 6, which will preferably be formed integral with the part 1 and extend somewhat beyond the center or axis of the casing and 50 sufficiently to allow the throttling valve 7 to take a position with its opening 8 axially in the casing 1, and so as to register with the axial opening through the casing 1. The valve casing 6 is closed at its outer end by a head 9, which is removable to allow the valve 55 7 to be removed or returned to its position in the case, and the valve 7 is provided with a valve stem 10 ex-

tending to the outer side of the head 9, where it is provided with a lever 11 by means of which the operation of the valve 7 may be controlled. The valve 7 is of a cylinder form, and the opening 8 therethrough is enlarged on the receiving side of the valve, as shown by the dotted lines in the plan view in Fig. 6, and also shown in the side elevation of Fig. 4. The discharge end of the carbureting nozzle 12 is located centrally within the valve 7 and also centrally within the valve 65 axial passage through the receptacle 1, and communicates with the interior of the receptacle 1 through the passage a shown in dotted lines in Fig. 1, together with the several small perforations b in the bottom of the receptacle, also shown in dotted lines in Fig. 1. 70 and in plan view in Fig. 3. The passage a is provided for in the thickened bottom head 3 of the receptacle, and this passage is controlled by a needle valve 14 shown in dotted lines in Fig. 1, the same having on the outer end of the stem a head 15, by means of 75 which it may be operated.

In order to catch any drip from the nozzle 12, there is provided below the lower end of the opening, through the casing, a pan 15. This pan may be supported by a stem 16 engaging with the lower end of 80 the nozzle 12, and, in order to give it more stability, provided with posts 17 which will strike against the under side of the receptacle head and prevent undue strain being placed on the stem 16 from a pressure or blow on the pan. Within the receptacle 1, which 85 may also be termed a float chamber, there is provided a float 18. This float is preferably of cork and cut out, as shown, to provide clearance around the valve chamber 6. The float 18 is attached to the swinging end of an arm 19, which arm is pivoted at 20 in an 90 extension 1^a of the case. The arm 19 carries a socket 19^a which receives a cork 21, which cork acts as a closure, when the float is in upper position, for the nozzle 22. The nozzle 22 is screw-threaded through the upper wall of the case extension 1^a and has connected therewith a tube 23, which supplies the carbureting fluid. 95

When carbureting fluid has entered the float chamber to sufficient depth to operate the float, the cork stopper 21 will engage with and close the lower end 100 of the nozzle 22, and when the float takes a lower position by reason of a portion of the contents of the float chamber having been removed, the valve will open and allow more fluid to enter the chamber. By this arrangement, the surface of the carbureting fluid 105 within the float chamber is maintained at a substantially uniform level, and the arrangement is such that this level will ordinarily be a trifle lower than the discharge end of the carbureting nozzle 12. The discharge end of the carbureting nozzle 12 being thus 110, located in the center of the surface of the fluid in the float chamber, there is no danger of flooding the nozzle.

zle by throwing the carbureter out of its normal horizontal plane, for while the depth of the fluid may increase in one side of the float chamber and decrease in the other side, this does not affect the central point 5 at which the carbureting nozzle is arranged. The valve 7 is provided with a cut-out, as shown at 7^a, in one of its walls so as not to interfere with the carbureting nozzle 12, which extends up the center of the passage way, through the carbureter. In other words, 10 the cut-out 7^a allows the valve 7 to be turned to its closed position, which otherwise would be prevented by the nozzle.

By reason of the opening 8 through the valve 7 being larger on the receiving side than on the discharge side when the valve 8 is nearly closed, the operation 15 of the current of air as it picks up the carbureting fluid from the end of the nozzle 12 is somewhat peculiar. While the air passing through the more restricted opening at the discharge side of the valve 7 may cause 20 the current of air to pass rapidly on account of the decrease in size of the opening above the nozzle, the current of air around the nozzle passes less rapidly and thereby produces less suction on the nozzle than might otherwise occur. In this way this carbureter 25 serves to some extent to proportion the amount of carbureting fluid received from the nozzle 12 to the amount required when the passage is throttled more or less.

It will be noted that any drip from the nozzle 12 30 which may be caught in the pan 15 will be absorbed by the air which passes over the edges of the pan, and thence to the axial opening through the carbureter, as shown by the arrows in Fig. 2. This pan 15 in start-

ing may also be supplied with a charge of gasoline, in order to provide an extra rich mixture for the purpose 35 of starting, if desired.

The operation of carbureters is too well understood to warrant further description of the mode of operation. It is evident that changes and modifications from the construction shown may be made without departing 40 from the spirit of my invention.

What I claim as new and desire to secure by Letters Patent is:

1. The combination in a carbureter of a float chamber having an axial passage through the same, a valve located in and arranged for throttling, the said passage at two points, a carbureting nozzle arranged within said passage between the two throttling points and communicating with the interior of the float chamber, means for applying carbureting fluid to the float chamber, a float, 45 and a valve controlled by the float and controlling the supply to the float chamber, substantially as set forth.

2. The combination in a carbureter of a hollow body constituting a float chamber having an axial passage therethrough and a radial chamber from said axial passage, of a valve arranged in the radial chamber and adapted to throttle the axial passage at two points, the carbureting nozzle arranged within said passage and between the two throttling points and communicating with the interior of the float chamber, means for supplying carbureting fluid to the float chamber, a float in the float chamber, and a valve controlled by the float and controlling the supply to the float chamber, substantially 55 as set forth.

In witness whereof, I have affixed my signature, in 60 presence of two witnesses, this 5th day of Oct. 1905.

HARRY B. MAXWELL.
